EUGENE F. CLARK, OF DAMARISCOTTA, MAINE, ASSIGNOR TO MARSHALL FIELD MILLS CORPORATION, OF PHILADELPHIA, PENNSYLVANIA, A CORPORATION OF PENNSYLVANIA

TUFT YARN FRAME FOR LOOMS FOR WEAVING TUFTED PILE FABRIC

Refile of application Serial No. 454,949, filed May 23, 1930. This application filed June 18, 1931. Serial No. 545,293.

This invention relates to improvements in tuft yarn frames or carriers for carrying and delivering the tuft yarns in looms for weaving tufted pile fabric.

5 The tuft yarn frames employed in these looms are each provided with a single spool or a number of alined spools carrying a plurality of tuft yarn strands and they are each provided with a row of passages for 10 receiving the delivery end portions of the strands from the spool and for maintaining them in proper lateral spaced relation.

A number of these frames are mounted in spaced parallel relation on a pair of carrying 15 chains which are actuated to bring the frames successively into a yarn delivering position, and each time a frame is brought into such position, instrumentalities of the loom act upon the delivery end portions of the yarn 20 strands and draw them through the passages, and, thereafter, a cutting device cuts from the strand parts of sufficient length to form pile tufts, and leaves the ends of the yarn strands in position with relation to the frame 25 or carrier to be acted upon by the instrumentalities of the loom the next time the frame or carrier is brought into the yarn delivering position.

The object of my invention is to provide a 30 novel and advantageous means for producing friction upon the yarn strands when they are drawn through the yarn passages, and, thereafter, for holding the delivery end portions of the strands in even and uniform relation to the frame or carrier so that each time the frame or carrier is brought into the yarn delivering position, yarn tufts of uniform length will be cut from the strands.

35 The invention resides in the novel construction, combination and arrangement of elements hereinafter described and claimed.

In the accompanying drawing, illustrating the invention,

40 Figure 1 is a front view of one end portion of a tuft yarn frame, showing one form of embodiment of my invention, illustrating only a portion of the yarn strands on the spool carried by the frame.

45 Figure 2 is a transverse section through the same, on line 2—2 of Fig. 1.

55 Referring to the drawing, 3 designates the long body bar of the tuft yarn frame, 4 one end portion of a spool carried by the frame, and 5 the tuft yarn strands carried by the spool.

The bar 3 is provided with suitable bearing arms for rotatably supporting the respective ends of the spool, one end portion of the spool 4 and a bearing arm 6 supporting it being shown in Fig. 1.

60 The respective ends of the body bar 3 are provided with oppositely disposed chain engaging arms and latches like the arm 7 and latch 8 shown in Fig. 1, for connecting the frame to the chains of the loom which carry 65 the series of tuft yarn frames thereof and bring them successively into the yarn delivering position.

65 The bottom of the body bar 3 is provided with a row of transversely extending, laterally spaced plates 9 which are suitably connected to and project from a longitudinally extending angle bar 10 secured to the bottom of the body bar. These plates 9 extend forwardly, of the forward surface 11 of the 70 body bar 3 and provide passages 12 between them through which the free or delivery end portions of the tuft yarn strands 5 are drawn, the plates 9 serving to maintain the free end 75 portions of the strands in lateral spaced 80 relation.

85 The plates 9 are provided with forward and rearward, laterally extending projections, 13 and 14, respectively, between which the yarn strands 5 extend. These projections serve to prevent forward and rearward displacement of the strands 5 within the 85 passages 12.

90 The parts providing the yarn passages 12 may be of any suitable form. The plates 9 herein illustrated which form the passages 12 are designed for use in looms in which grippers are employed which enter the passages or spaces between the plates 9 and grasp the end portions of the strands 5 there- 95 in and draw them from the spool 4 and through the passages 12 until there is sufficient yarn extending below the line 15 to form pile tufts, whereupon the pile tufts are 100 cut from the strands on the line 15 and sub-

sequently woven into the fabric being produced by the loom. This operation is performed each time the frame is brought into the yarn delivering position.

5 Arranged adjacent to the forward surface 11 of the body bar 3 and extending longitudinally thereof, in parallel relation thereto, is a relatively thin, flat steel spring 16 between which and the forward surface 11 of the body 10 bar 3 the yarn strands 5 are drawn when the strands are drawn through the passages 12 by the grippers. This spring or element 16 is supported at suitable intervals throughout the length of the body bar 3 by narrow brackets 17 which embrace the spring 16 and have their end portions soldered or otherwise suitably secured to the bar 3. The brackets 17 are arranged above and in alignment with certain of the plates 9 so that the strands 5 15 may pass the brackets on the respective sides thereof without interference as the strands pass from the spool 4 to the passages 12.

The spring or element 16 may be removed from the body bar 3 by withdrawing it longitudinally from within the brackets 17, and it is inserted into the brackets 17 forwardly of the yarn strands 5 after the strands have been inserted into the passages 12.

30 The spring or element 16 is located a slight distance above the forwardly projecting portions of the plates 9 and it extends over all the yarn strands 5 which pass from the spool 4 to the passages 12. The space between the spring 16 and the forward surface 35 of the bar 3 is slightly less than the general normal diameter or thickness of the yarn strands 5 so that the strands will be compressed slightly as they pass between the spring and the bar, thereby causing the 40 spring and bar to press against the strands and retard the movement thereof toward the passages 12.

45 The elastic character of the spring or element 16 permits it to yield outwardly from the bar 3 to permit any irregularities in the diameter or thickness of the strands 5 to pass between the element 16 and bar 3, the element 16 returning automatically to normal relation with the bar 3 after the passage of such 50 irregularities.

55 When the strands 5 are drawn through the passages 12, as previously described, the pressure of the spring or element 16 against them will produce sufficient friction to cause all the strands to be drawn through the passages under substantially the same degree of tension.

60 After the strands 5 have been drawn through the passages 12 and cut on the line 15, as previously explained, the pressure of the spring or element 16 against them will hold them in the same position with respect to the bar 3 which they occupied previously to the cutting operation and prevent either 65 the natural elasticity inherent in the strands

or the tendency thereof to resume the curvature of their previously occupied positions on the spool 4 from causing any of the strands to move back or withdraw from the position which they occupy within the passages 12 at the time the cutting operation takes place. Therefore, each time pile tufts are cut from the strands 5, the delivery end portions of the strands will be left in an even row to be engaged by the loom gripper or other devices prior to the next succeeding cutting operation, resulting in the desired removal of pile tufts of uniform length from the strands 5 at each cutting operation.

This application is a refiling of application Ser. No. 454,949.

I claim as my invention:

1. In a tuft yarn frame, a body bar provided with spool supporting means and provided also with parts forming a row of passages for yarn strands and a yieldable element carried by and extending longitudinally of the bar and having an uninterrupted surface extending continuously across the paths of a multiplicity of yarn strands passing from a spool supported by said means to said passages and constructed to engage and press against the strands.

2. In a tuft yarn frame, a body bar provided with spool supporting means and provided also with parts forming a row of passages for yarn strands and a yieldable element carried by and extending longitudinally of the bar across the paths of yarn strands passing from a spool supported by said means to said passages and constructed to engage and press against the strands and means carried by the bar for detachably connecting said element thereto, said element being movable longitudinally into and from engagement with the last named means.

3. In a tuft yarn frame, a body bar provided with spool supporting means and provided also with parts carried by the bar and extending forwardly from the lower portion thereof and forming a row of passages for yarn strands and a single, yieldable, friction producing element carried by the bar above said parts and constructed to press against a multiplicity of yarn strands passing from a spool supported by said means to said passages.

4. In a tuft yarn frame, a body bar provided with spool supporting means and provided also with parts forming a row of passages for yarn strands, a friction producing element carried by and extending longitudinally of the bar for engaging yarn strands passing between the element and the bar to said passages and means for detachably connecting said element to the bar at spaced points longitudinally of the element.

5. In a tuft yarn frame, a body bar provided with spool supporting means and provided also with parts forming a row of pas-

sages for yarn strands and a single, yieldable, friction producing element carried by the bar and having an uninterrupted surface constructed to engage a multiplicity of yarn strands passing between the element and the bar to said passages.

6. In a tuft yarn frame, a body bar provided with spool supporting means and provided also with parts carried by the bar and 10 extending forwardly from the lower portion thereof and forming a row of passages for yarn strands, a friction producing element carried by and extending longitudinally of the bar above said parts for engaging a multiplicity of yarn strands passing between the element and the bar and means for detachably connecting said element to the bar.

7. In an individually transportable tuft yarn carrier for looms, a frame or carrier 20 proper, spool supporting means thereon, a series of yarn guides along and secured to said frame or carrier, and a resilient yarn-tensioning sheet-metal strip for and common to a multiplicity of said guides, said strip being 25 carried by and in substantial parallelism with the frame or carrier as a whole for movement into and out of tensioning relation to the yarns to be guided.

8. In a tuft yarn frame, a body bar provided with spool supporting means and provided also with parts forming a row of passages for yarn strands, a yieldable element carried by and extending longitudinally of the bar across the paths of a multiplicity of 35 yarn strands passing from a spool supported by said means to said passages, and constructed to engage and press against the strands and brackets carried by said bar at spaced points longitudinally thereof and 40 having aligned openings therein through which the element extends.

In testimony whereof I affix my signature.
EUGENE F. CLARK.
